UNITED STATES PATENT OFFICE.

LEWIS T. WILCOX, OF PEEKSKILL, NEW YORK.

DESIGN FOR A STOVE LEG.

Application filed October 15, 1927. Serial No. 23,754. Term of patent 14 years.

To all whom it may concern:

Be it known that I, LEWIS T. WILCOX, a citizen of the United States, and a resident of Peekskill, in the county of Westchester and State of New York, have invented and produced a certain new, original, and ornamental Design for Stove Legs, of which the following is a specification, reference being had to the accompanying drawings, forming part thereof, wherein:

Fig. 1 is a side view of the article showing my new design;

Fig. 2 is a sectional view taken on line 2—2 of Fig. 1, and,

Fig. 3 is a sectional view taken on the line 3—3 of Fig. 2.

My invention comprises a stove leg having a rectangular plane sided upper portion which engages the corner of a stove and which merges at its lower end, immediately below the point of its engagement with the stove, into a semicircular portion, and then into a rounded circular portion at its lower extremity.

I claim:

The ornamental design for a stove leg, as shown and described.

LEWIS T. WILCOX.
